UNITED STATES PATENT OFFICE.

FRANK B. SMITH, OF PHILADELPHIA, PENNSYLVANIA, ASSIGNOR TO THE BARBER ASPHALT
PAVING COMPANY, OF PHILADELPHIA, PENNSYLVANIA, A CORPORATION OF WEST
VIRGINIA.

MIXER-OPENING DEVICE.

No. 892,321.

Specification of Letters Patent.

Patented June 30, 1908.

Application filed January 15, 1907. Serial No. 352,396.

To all whom it may concern:

Be it known that I, FRANK B. SMITH, of Philadelphia, in the State of Pennsylvania, have invented certain new and useful Improvements in Mixer-Opening Devices, whereof the following is a specification, reference being had to the accompanying drawings.

My invention relates to devices for opening mixers such as are employed for mixing the ingredients used in the manufacture of asphalt paving.

The object of my device is to provide a fluid actuated device for opening such a mixer; the fluid used being preferably compressed air or steam.

In the accompanying drawings, Figure I, is a plan view showing a mixer with my improved opening device attached thereto. Fig. II, is a vertical section on the line II, in Fig. I.

In said drawings, 1, represents the receptacle in which the material is placed and mixed by means of the revolving blades 2. The bottom 14 of the receptacle is provided with a rectangular opening 3, through which the contents of the mixer may be discharged said opening being closed by a sliding closure or slide bar 4, on the lower side of the receptacle. This closure comprises a plate 5, best shown in Fig. I, which may be made to register with the opening 3, of the mixer body when desired. This slide plate is shaped on its upper surface to conform to the outside of the bottom of the receptacle and is provided at each end with a projection or guide lug 6, 7, which pass through openings 8, and 9, respectively in the ends 10, 11, of the receptacle below the bottom thereof. These openings 8, and 9, serve to guide the slide plate and maintain it in proper relation to the opening 3, in the bottom of the receptacle.

Below the slide plate 4, are the rollers 12, 13, journaled in brackets 15, 16, respectively, which are secured to the ends 10, 11, of the receptacle in any approved manner. The rollers are so located as to be in line with the projections 6, 7, on the slide plate, and thereby form a support for said plate. Attached to the under side of the plate 5, by means of bolts 18, 19, is a shoulder block 17, to which is secured one end of the piston rod 20, of the mixer opening device. To one end 10, of the

receptacle below the line of travel of the slide bar, and its projection 6, is attached a cylinder 22, by means of casting 23, forming one head of the cylinder, said casting being provided with side flanges 24, through which the bolts 25, are passed, to securely fasten the cylinder to the end of the mixer. By thus locating the cylinder and connecting its piston 21, to the under side of the slide plate 5, by means of the piston rod 20, and the shoulder block 17, a direct thrust may be exerted upon the block to move the slide plate, and all the opening mechanism is so located as not to interfere with the operation of the mixing mechanism, thus making a compact and efficient device.

The mixer opening device comprises the cylinder 22, provided with pipes for supplying compressed air or steam thereto, and also provided with means for exhausting such air or steam therefrom. The compressed air may be obtained by means of piping from a compressor situated at some other portion of the plant and driven by an engine, or steam may be supplied from the boiler used for furnishing steam for running the plant. The supply pipe 30, is provided with a four-way valve 31, which may be controlled by means of a wrench or in any other suitable manner, and to this valve is also connected the exhaust pipe 32.

From opposite sides of the valve 31, and extending parallel with the cylinder, are pipes 34, and 35, each provided with tees 36, and 37. The lower end of the tee 36, is connected to the pipe 40, which connects with the forward end of the cylinder 22, and the lower end of the tee 37, is connected by means of a pipe 41, with the rear end of the cylinder 22. Extending from the forward end of the tee 36, is a pipe 44, connecting with the cylinder at a point between the forward end and the center thereof, and at the rear end of the tee 37, is a similar pipe 45, connecting with the cylinder at a point between the center and rear end.

In the position shown in the drawings the mixer is closed and the piston is at the extreme right hand of the cylinder. If now the four-way valve be turned so as to admit air or steam, (depending upon which fluid is being utilized), the fluid passes from the pipe 30, through the valve 31, through the pipe

35, tee 37, pipe 41, to the rear of the cylinder and back of the piston 21. The pipe 41, is provided with a plug cock 42, for regulating the amount of flow through said pipe. Usually the cock will be so adjusted that only a small amount of the fluid will enter the cylinder back of the piston when the device is started so that it will move slowly at first until the rear of the piston passes the opening 10 of the pipe 45, in the cylinder, whereupon, the full force of the pressure is exerted upon the piston and it is moved quickly thereby moving the slide plate 5, quickly and opening the mixer to discharge its contents. As the 15 piston travels toward the left hand end of the cylinder the fluid at that end of the cylinder is compressed and the four-way valve is so constructed that the fluid may be exhausted through the pipes 40, and 44, into the exhaust pipe 32. The pipe 40, is also provided with a plug cock 43, similar to that in the pipe 41, and by adjusting the same a cushion may be formed at the left hand end of the piston when that end has passed the opening 20 of the pipe 44, thereby preventing the knocking out of the cylinder head. To close the mixer, the four-way valve is turned to admit the fluid under pressure to the forward end of the cylinder and the opening in the plug cock 25 43, being small, the piston travels slowly toward the right until it passes the opening of the pipe 44, whereupon, the full pressure is exerted upon the piston and it moves quickly to close the mixer. It is understood that the 30 plug cock 42, restricts the exhaust from the right hand end of the cylinder and thereby 35

a cushion is formed as explained above with regard to the left hand end.

I claim:—

1. A mixer having in combination a receptacle, the ends of which are provided with openings; a slide plate provided with guide lugs to fit said openings; a bottom for said receptacle provided with a discharge opening, said opening being normally closed by said 40 slide plate; a shoulder block on the under side of said slide plate; a piston rod connected to said shoulder block and extending in the direction in which said slide plate is moved to uncover said discharge opening; 45 and a cylinder in line with said piston rod.

2. A mixer having in combination, a receptacle the ends of which are provided with openings; a slide plate provided with guide lugs to fit said openings; rollers mounted to 50 support said slide plate; a bottom for said receptacle provided with a discharge opening, said opening being normally closed by said slide plate; a shoulder block on the under side of said slide plate; a piston rod 55 connected to said shoulder block; and a cylinder mounted to lie below the line of movement of the lugs on said slide plate and co-operating with said piston rod.

In testimony whereof, I have hereunto 60 signed my name, at Philadelphia, Pennsylvania, this ninth day of January 1907.

FRANK B. SMITH.
